United States Patent Office

Des. 186,365
Patented Oct. 20, 1959

186,365

AUTOMOBILE

Clare M. MacKichan, Farmington, Mich., assignor to
General Motors Corporation, Detroit, Mich., a cor-
poration of Delaware

Application February 24, 1959, Serial No. 54,714

Term of patent 7 years

(Cl. D14—3)

Fig. 3

Fig. 4

Figure 1 is a side elevational view of an automobile embodying my new design;

Figure 2 is a perspective view;

Figure 3 is a front elevational view; and

Figure 4 is a top plan view.

The dominant features of my new design reside in the full line portions of the drawings.

I claim:

The ornamental design for an automobile, substantially as shown and described.
